UNITED STATES PATENT OFFICE.

GEORGE E. CURTISS, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A TEA OR COFFEE POT.

43,671.

Specification for Design.

Patented Mar. 4, 1913.

Application filed December 14, 1912. Serial No. 736,845. Term of patent 7 years.

To all whom it may concern:

Be it known that I, GEORGE E. CURTISS, a citizen of the United States, residing at New Britain, in the county of Hartford and State of Connecticut, have invented a new, original, and ornamental Design for a Tea or Coffee Pot, of which the following is a specification, reference being had to the accompanying drawing, forming part thereof.

The figure shown therein is a side eleva-

tion of a tea or coffee pot showing my new design.

I claim:

The ornamental design for a tea or coffee pot as shown.

GEORGE E. CURTISS.
